UNITED STATES PATENT OFFICE.

EDWARD B. COOPER, OF OAK LANE, PENNSYLVANIA.

PARALLEL-ADJUSTMENT MECHANISM FOR CAMERAS.

1,071,299.

Specification of Letters Patent.

Patented Aug. 26, 1913.

Application filed November 13, 1912. Serial No. 731,063.

To all whom it may concern:

Be it known that I, EDWARD B. COOPER, a citizen of the United States, and a resident of Oak Lane, in the county of Philadelphia and State of Pennsylvania, have invented 5 certain new and useful Improvements in Parallel-Adjustment Mechanism for Cameras, of which the following is a specification.

10 Objects of the present invention are to provide for accurately, easily and rapidly adjusting the front and back of a camera, or the like, while maintaining parallelism of the elements in all positions; to provide 15 ample and sufficient rigidity in lateral direction; to improve, simplify and lighten the means and mechanism by which the front and back are adjusted in focusing, and to provide adjusting means which not 20 only support the front and back and the parts carried thereby, but also serves to shift both the front and back in respect to the middle.

The invention will be claimed at the end 25 hereof, but will first be described in connection with the embodiment of it chosen, among other embodiments of it, for illustration in the accompanying drawings, in which—

30 Figure 1, is a top or plan view, partly in section. Fig. 2, a side view partly in section on the line 2—2 of Fig. 1. Fig. 3 is an end view partly in section of the central frame and support, and Fig. 4, is a side 35 view similar to Fig. 2, with the bellows closed.

In the drawings 1 and 2 are the front and back of a camera, or in other words, the two elements which are to be shifted in 40 parallelism in order to focus. Each of these elements is provided at either side with a pivot 3, and with a slidable carriage 4, the latter running in ways 5, slotted at 6 and formed in the vertical sides of the parts 1 and 2. Each carriage may be provided with 45 rollers, of which some 7 bear on one wall of the ways and of which the others 8, bear on the opposite walls of the ways. The frame consists of a base 9 carried by the 50 support 10 which may include a universal joint and tripod, not shown, because they are well understood. The frame also comprises a top member 11 and a pair of standards 12. Each standard is provided with a 55 pair of arm-guides or slots 13 and 14 and with a nut-guide or slot 15. 16, are nuts

arranged in the nut-guides or slots 15. 17 and 18 are oppositely disposed brackets connected with the nuts and standards. The screws 19, bevel gears 20 and 21, shaft 60 22 and handle 23 constitute a screw-gear for working the nuts.

There are pairs of crossed pivotal arms 24 and 25 having complementary circular parts 26 and circular ways 27. 28, are the 65 pivots for these arms and at 27 the arm 24 has a circular undercut that receives the beveled edge 29 of the arm 25. The object of this construction, as of the construction to be further described, is to impart lateral 70 rigidity. One of the ends of the arms of each pair works through one of the arm slots and is pivotally connected with the brackets 17 and 18 and the other ends of the arms of the pair are pivotally connected 75 with a carriage 4 and a pivot 3.

30 is the bellows.

Evidently by turning the handle 23 the 80 nuts 16 are shifted up or down, turning the pairs of arms about their centers 28 and thus shifting the elements 1 and 2 toward and away from the frame and toward and away from each other. This is the movement required for focusing. The described 85 pivotal connection between the arms of each pair, as well as the arrangement of the arms so as to work in the arm slots, gives the camera the necessary rigidity. The frame and the arms constitute the sole support of the camera so that it can be folded 90 into a very compact space as shown in Fig. 4, while at the same time it can be made as long as necessary.

What I claim as new and desire to secure 95 by Letters Patent is—

1. The combination with two elements to be shifted in parallelism of, a frame between the elements and provided with fixed pivots, a pair of nuts vertically movable in the frame and provided with pivots, a screw 100 gear for working the nuts, and pairs of crossed pivotal arms, one arm of each pair having one of its ends pivoted to one of said frame pivots and the other of its ends slidably and pivotally connected with one of 105 said elements and the other arm of the pair pivoted at one end to one of said elements and pivoted at the other end to one of the nut pivots, substantially as described.

2. The combination with the two elements 110 to be shifted in parallelism of pivots and slidable carriages carried respectively by

said elements, fixed standards each provided with a pair of arm-guides or slots and with a nut-guide or slot, nuts respectively arranged in the nut-guides or slots, oppositely disposed brackets connected respectively with the nuts and standards, a screw-gear for working the nuts, and pairs of crossed pivotal arms having complementary circular center parts and circular ways and having one of the ends of the arms of each pair working through one of the arm slots and respectively pivotally connected with said brackets and the other ends of the arms of the pair respectively connected with said carriage and pivot, substantially as described.

3. The combination with the two elements to be shifted in parallelism, of standards each provided with a pair of arm-guides or slots, nuts movable in respect to the respective standards, a screw-gear for working the nuts, and two pairs of crossed pivotal arms for each standard, each pair of arms having complementary circular center parts and circular ways and having one of the end por-

tions of each arm of each pair working through one of the arm slots and respectively suitably connected with the nut and bracket and the other of the ends of the arms of the pair suitably connected with 30 said elements, substantially as described.

4. The combination with the two elements to be shifted in parallelism, of standards, brackets respectively movable in respect to the standards, means for moving the brackets, and pairs of crossed pivotal arms having complementary circular parts and circular ways and having one of the ends of the arms of each pair respectively pivotally connected with one of said brackets and with one of 40 the standards and the other ends of the arms of the pair and slidably pivotally connected with one of said elements, substantially as described.

In testimony whereof I have hereunto 45 signed my name.

EDWARD B. COOPER.
